UNITED STATES PATENT OFFICE

ABRAM LOCKHEART ZENT, OF DAYTON, OHIO

MACHINE FOR VENDING STAMPS AND THE LIKE

Application filed December 19, 1929. Serial No. 415,218.

This invention relates to a machine for vending stamps and the like.

One object of the invention is to provide a simple efficient mechanism which will accurately deliver a number of stamps corresponding to the value of a coin inserted in the machine.

A further object of the invention is to provide an improved coin controlled selecting device to determine the number of stamps delivered.

A further object of the invention is to provide a selecting mechanism of such a character that the operation thereof will not be interfered with by the insertion of two or more coins prior to the operation of the machine, but which will act on the coins successively to cause the proper number of stamps to be delivered for each coin.

A further object of the invention is to provide such a machine having means for exposing to view the coin last operated on until another coin has been inserted and the machine operated.

A further object of the invention is to provide such a machine having means to prevent the delivery of stamps when a washer or similar article is inserted in the coin chute.

Other objects of the invention will appear as the mechanism is described in detail.

In the accompanying drawings Fig. 1 is a front elevation of a machine embodying my invention; Fig. 2 is a top plan view of the machine, partly broken away and with the cabinet removed; Fig. 3 is a rear elevation of the mechanism with the cabinet removed; Fig. 4 is a side elevation of a mechanism at the left hand side of the machine, as shown in Fig. 1; Fig. 5 is a vertical sectional view taken on the line 5—5 of Fig. 1, omitting the cabinet; Fig. 6 is a side elevation of the mechanism at the right hand side of the machine, as shown in Fig. 1; Fig. 7 is a detail view of the selecting and operating mechanism showing the positions of the parts when a five cent coin is in the chute; Fig. 8 is a similar view showing the position of the parts when a ten cent coin is in the chute; Fig. 9 is a sectional detail view of the operating shaft and cam, Fig. 10

is a side elevation of one of the groups of cams; and Fig. 11 is a sectional detail view.

In these drawings I have illustrated one embodiment of my invention but it will be understood that this embodiment has been chosen for the purposes of illustration only and that the mechanism may take various forms and may be arranged in various ways without departing from the spirit of the invention. The present machine is designed primarily for vending postage stamps but it will be understood that it may be utilized for vending articles of various kinds which are connected in strips having one or more perforations or openings between adjacent articles. The term "stamp" as herein used is intended to include not only postage stamps but other similar articles.

The machine here illustrated is adapted to deliver stamps of any one of a plurality of denominations at the option of the purchaser and to deliver a number of stamps of a selected denomination determined by the value of the coin deposited in the machine. This particular machine vends one cent stamps and two cent stamps at a profit and is adapted to receive either a five cent coin or a ten cent coin. When a nickel is inserted in the machine and the machine operated there will be delivered either four one cent stamps or two two cent stamps, depending upon the selection made by the purchaser. If a dime is inserted in the machine either eight one cent stamps or four two cent stamps will be delivered, again depending upon the selection made by the purchaser. The machine comprises two vending units, one for one cent stamps and one for two cent stamps and these vending units are separate one from the other with the exception that certain parts of the operating mechanism are common to both units.

As here shown, the machine comprises a cabinet 11 within which is mounted a frame 12 on which the mechanisms are supported, the vending unit for the one cent stamps being at the left hand side of the cabinet, as shown in Fig. 1, and the vending unit for the two cent stamps being at the right hand side of that cabinet. If desired, the cabinet may

be provided in one or more walls thereof with glass panels 13 through which the operation of the mechanism may be observed. At the upper end of the cabinet are coin slots 14 and 15 which communicate with the coin chutes of the respective vending units. Arranged in the forward portion of the cabinet and between the two vending units is a delivery chute 16 which terminates at its lower end in a delivery receptacle or pocket 17 which is accessible from the exterior of the cabinet. The two vending units are substantially identical and it will be understood that the description of one of these units applies equally to the other.

The stamp strips may be supported in the machine in any suitable manner. Postage stamps may be secured in rolls and the present machine is provided with a series of reels adapted to receive such rolls, one of these reels being shown at 18. The several reels are mounted on a shaft 19 which is carried by arms or brackets 20 secured to the respective side members of the frame 12. Inasmuch as the two vending units are identical and each advances the stamp strip the same distance as does the other it is necessary to utilize two strips of one cent stamps which will be advanced simultaneously and, in the present machine, there are three reels, one adapted to receive a roll of two cent stamps and the other two adapted to receive rolls of one cent stamps. Each stamp strip is led from its roll forwardly through a guideway 21, the forward end of which communicates with the delivery chute 16. When the desired number of stamps has been feed forward into the chute they are severed, in a manner to be hereinafter described, and dropped through the chute 16 to the delivery pocket 17. The feeding mechanism which advances the stamp strip is here shown as comprising a driven roller 22 and a pressure roller 23, there being a separate pair of rollers for each stamp strip. The driven rollers are preferably frictionally driven so that they will advance the stamp strips under normal conditions but if the movement of a strip is interrupted or excessive resistance is offered to its movement the operating mechanism may move with relation to the roller and thus avoid injuring the mechanism. As here shown, the several driven rollers 22 are loosely mounted on a single shaft 24 which is supported in the side members of the frame 12 and one end of which extends beyond the cabinet and has secured thereto a crank 25 or other suitable means for rotating the same. The rollers are arranged between friction disks 26 carried by spacing sleeves 27 and collars 28 which are rigidly secured to the shaft. Mounted in each lateral face of each roller is a plurality of friction members or small plungers 29 which are pressed outwardly into frictional

contact with the respective friction disks 26 by springs 30, thereby frictionally connecting the roller with the shaft. The lower or pressure rollers 23 are supported by pivoted brackets 31 each of which has a downwardly extending portion 32 which is acted upon by a spring 33 to move the roller 23 toward the driven roller and thus cause the stamp strip to be gripped between the two rollers. The pressure roller engages the gummed side of the stamp and to prevent the possibility of the stamp sticking to the roller, due to long continued pressure thereon, I have provided means for retracting the pressure roller and holding the same normally in an inoperative position. For this purpose the downwardly extending part 32 of the bracket 31 has a part 34 arranged to be engaged by a lug or cam 35 on an operating shaft 36 which controls the operation of the mechanism, as hereinafter described. The cam 35 is so arranged that at the end of each delivery of stamps it will engage the part 34 of the bracket and move the bracket about its axis in a direction to withdraw the pressure roller from the driven roller. A detent 37 engages a pin 38 on the bracket and retains the pressure roller in its inoperative position until the detent is actuated to release the same at the beginning of another operation.

The stamp strip is held normally against movement in the guideway 21 by a detent 39 arranged to enter the perforation or perforations between adjacent stamps and, in the present instance, comprise a series of spring fingers having downturned ends to extend through openings in the upper and lower walls of the guideway and through the perforations in the stamp strip. The yieldable fingers are so arranged that the resiliency thereof will tend to hold them normally in their operative positions, in which the stamp strip is held against movement. The detent is moved to its inoperative position by a suitable lifting device which is here shown as a lever 40 pivotally mounted between its ends on lugs 41, carried by the top wall of the guideway 21, and having at its forward end downwardly extending parts in which is mounted a rod 42 which extends transversely to and beneath the resilient fingers 39. The rear end of the lever 40 is depressed by means of a cam 43 which is held normally in an inoperative position by a spring 44. The cams 43 for the detents which act on the two one cent stamp strips are secured to a shaft 45 having at one end thereof a crank arm 46 and the cam 43 for the two cent stamp strip is secured to a tubular shaft 47 mounted on the shaft 45 and having at its outer end a crank arm 48. If desired, each cam may have a finger piece 49 by means of which it may be actuated to depress the rear end of the lever and thus

move the detent to its inoperative position when it is desired to insert or remove the stamp strip.

Suitable means are provided for actuating the shafts 45 and 47 to release the respective stamp strips and permit the same to be advanced by the feed rollers a distance determined by the denomination or size of the coin which has been inserted in the machine. In the present instance, this is accomplished by means of an actuating device comprising an arm 50 pivotally mounted on a stud 51 and having an actuating finger 52 pivotally supported on the free end thereof. The upper end of the actuating finger is movable into operative relation with either of two contact parts 53 and 54 carried by and forming parts of an intermediate member 55 which is pivotally mounted on a shaft 56 and which is connected by a link 57 with the crank arm 48 of the shaft carrying the detent operating cam 43. As here shown, the link 57 has at its outer end a longitudinal slot 58 to receive a stud or pin 59 on the crank arm 48. This pin is normally held in the lower end of the slot by the spring 44 so that the crank arm will be operated by any upward movement of the link, but the crank arm may be moved with relation to the link when the cam 43 is actuated by its finger piece 49. Rigidly connected with the actuating arm 50 is an arm 60, the end of which is held in engagement with a cam 61 on the operating shaft 36 by means of a spring 62. The operating shaft has secured thereto a gear 63 which meshes with a gear 64 on the feed roller shaft 24 so that the operating shaft will be actuated whenever the crank 25 is actuated. The cam will act upon the arm 60 to move the arm 50 and the actuating finger 52 through a predetermined distance upon each rotation of the operating shaft and the length of the cam surface is, in the present instance, sufficient to hold the operating device in its elevated position, and thus hold the detent 39 in its inoperative position, through a period of time sufficient to permit the feed rollers to advance the strip a distance in excess of the length of one stamp. When the cam passes out of engagement with the arm 60 the operating device moves downwardly and releases the intermediate pivoted member 55. If this member is unrestrained it will be moved downwardly by a spring 150 which connects the same with the operating arm 50 and the action of the spring 44 on the cam 43 will return the cam to its normal position, thus permitting the detent 39 to engage the stamp strip. Inasmuch as the stamp strip has been advanced a distance in excess of the length of one stamp the detent will rest upon the second stamp in the strip, beyond the first row of perforations, and when the strip has completed a move-

ment equal to the length of two stamps the detent will enter the second row of perforations and prevent the further movement of the stamp strip, thus permitting two stamps to be moved beyond the guideway in a position in which they may be severed and delivered to the purchaser. It will be noted that the contact parts 53 and 54 are spaced different distances from the axis of the pivoted member 55 and consequently a given movement imparted to the actuating finger 52 will, when that finger is in engagement with the contact part 54, move the pivoted member 55 a greater distance than it will move that member when it is in engagement with the contact part 53. The position of the actuating finger is so controlled, in a manner hereinafter described, that when a nickel is in the coin chute the actuating finger will be supported in operative relation to the contact part 53 of the pivoted member, and when a dime is in the chute the finger will be supported in operative relation to the contact part 54. When the actuating finger is in engagement with the contact part 53 the member 55 will be released when the cam 61 passes out of engagement with the arm 60, thus permitting two stamps to be delivered for the nickel which is in the chute. When the actuating finger is in operative relation to the contact part 54 the further movement which is thus imparted to the pivoted member 55 will cause a detent or pawl 65 to engage a lug 66 on the pivoted member and retain the same in its elevated position after the actuating finger 52 has moved downwardly, thus retaining the detent 39 in its inoperative position for a longer period of time. The detent 65 has connected therewith an arm 67 acted upon by the spring 62 to move the detent 65 toward the member 55 and this arm is arranged to be engaged by a pin 68 carried by a part secured to the operating shaft 36. This pin is so arranged that it will engage the arm 67 and move the pawl 65 out of engagement with the pivoted member 55 after the stamp strip has been advanced a distance slightly greater than the length of three stamps, thereby permitting the detent to engage the upper surface of the fourth stamp and to enter the next series of perforations when the strip has been advanced a distance equal to the length of four stamps, thereby permitting four stamps to be advanced beyond the guideway and into positions in which they may be severed and delivered.

Associated with each vending unit is a coin chute 69 which chutes communicate respectively at their upper ends with the coin slots 14 and 15. Extending into each coin chute near the lower end thereof is a stop 70 which will arrest the downward movement of a coin and which may be moved 130

out of the path of a coin to permit the same to be discharged. An arm 71 is pivotally mounted alongside the chute, as shown at 72, and has its forward portion offset and 5 extended upwardly, as shown at 73, so that when the arm is moved about its axis the upper end thereof will enter the chute 69 and engage the edge of a coin supported on the stop 70. A spring 74 presses the end 10 of the arm against the coin and the movement thus imparted to the arm is determined by the diameter of the coin. Rigidly secured to the arm 71 is a second arm 76 which extends upwardly alongside the chute and 15 has at its upper end a forwardly extending portion provided with a lateral projection or stud 77 which engages the rear edge of the actuating finger 52. A spring 78 acts on the finger 52 to hold the same in contact 20 with the stud 77. The relative positions of the arms 71 and 76 are such that when the arm 71 is in contact with a five cent coin the actuating finger will be positioned in operative relation to the contact part 53 of 25 the pivoted member 55, (see Fig. 7), and when the arm 71 is in contact with a ten cent coin the actuating finger will be supported in operative relation with the contact part 54 of the pivoted member 55 (see Fig. 8). 30 The forward portion of the arm 71 has a laterally extending stud 79 which is engaged by an arm 80 pivotally mounted on the stud 51 and having an upwardly and forwardly extending portion or finger 81 arranged to 35 be actuated by a cam 82 on the operating shaft 36. When the cam 82 engages the finger 81 the arm 71 will be moved about its axis in a direction to withdraw the arm from the coin chute. When the highest point of 40 the cam is in contact with the finger the arm will be entirely withdrawn from the chute so that the latter will be unobstructed. When the finger 81 is in contact with the part 83 of the cam the finger 71 will project 45 into the chute a distance sufficient to interrupt the passage of any coin inserted therein, as shown in Fig. 6. The arm occupies this position during the time that the stop 70 is withdrawn so as to prevent a coin from 50 passing directly through the chute. The further operation of the cam will then withdraw the arm far enough to release the coin and permit it to drop into the stop 70 after which the high portion of the cam passes 55 beyond the finger 81 and the arm 71 is permitted to move inwardly until its movement is checked by the coin. In the present construction, I have shown at the rear of the chute an arm 84 pivotally mounted at 85 60 and extending downwardly to a point beyond the lower end of the chute 69 where it is provided with a laterally extending projection or lip 86 adapted to be moved into and out of line with the lower end of the chute. This arm has a forwardly extending 65 projection 87 adapted to extend through an opening in the rear edge of the chute 69 and to be engaged by a coin on the stop 70. The spring 78 is also connected with the 70 arm 84 and tends to move the same to its foremost position. The rearward movement of the arm is limited by a stud 88 so arranged that when the arm is in contact therewith the lip 86 will be substantially 75 out of line with the chute and the projection 87 will then constitute a fixed abutment against which the coin bears. When the coin moves out of line with the projection 87 the arm 84 will move forwardly and thus bring the lip 86 into line with the chute 80 and this movement will be effected in time to check the movement of the coin which has been released by the withdrawal of the stop 70 and thus cause that coin to be supported in a position in which it may be observed and its character determined through 85 the glass panel of the cabinet. 90 The stop 70 is carried by a lever 90 pivotally mounted at 91 on a vertical axis in front of the coin chute 69 and having an upwardly 95 extending arm 92 which carries a roller 93 which is arranged to be engaged by a face cam 94 on the operating shaft 36. A spring 95 acts on the lever 90 to hold the roller 93 against the cam and the cam is so arranged 99 with relation to the cams 61 and 82 that it will move the lever and stop 71 outwardly to release the coin at the end of each operation of the machine. As the coin moves out of engagement with the part 87 of the lever 100 105 84 this lever will be moved forwardly by its spring 78 and the lip 86 thereof positioned below the chute so that it will check the movement of the coin and support the same in a position in which it will be exposed to view until such time as another coin is inserted in the chute and forced against the lever 84 to retract the lip 86. The lever 90 has a second upwardly extending arm 96 which carries a pin 97 so arranged 110 that it may be moved into and out of the path of the actuating finger 52 by the movement of the lever 90 about its axis. The lever also carries a pin 98 arranged above the stop 70 and adapted to contact 115 with the coin in the chute. When the pin 98 is in engagement with a coin the lever 90 will be supported in such a position that the pin 97 will be out of the path of the actuating finger but if there is no coin in 120 the chute or if there is a washer in the chute, or some other device having an opening through which the pin 98 will extend, the lever will move inwardly far enough to position the pin 97 in front of the actuating finger and thus prevent that actuating finger from being moved into operative relation to the pivoted member 55. The movement of the selecting levers 71 and 76 will 125 take place as before but there will be no 130

release of the stamp strip and before the operating shaft completes its movement the lever 90 will be moved outwardly to withdraw the pin 98 and the stop 70 and permit the washer, check or other device to drop into contact with the lip 86 of the lever 84, where it will be exposed to view.

The detent 37 which retains the pressure roller 23 in its inoperative position, is secured to the shaft 56 which carries the pivoted members 55 so that when that member is moved upwardly to release the stamp strip the pressure roller will also be released and permitted to move into operative engagement with the stamp strip. In the present instance, this detent 37 is utilized to actuate a counter 99 of the conventional type, with which it is connected by a link 100. Inasmuch as the pivoted member 55 is moved different distances for the delivery of different numbers of stamps the counter will accurately register the number of stamps discharged. The stamps which are fed beyond the forward end of the guideway 21 are severed by a cutter or blade 101 which is rigidly secured to a shaft 102 mounted on one of the side members of the frame 12 and this shaft has a lateral projection 103, which preferably carries a roller 104, arranged to be engaged by a cam 106 on the operating shaft 36. A spring 107 acts on the shaft to hold the cutter normally in its elevated position and when the cam 106 acts on the roller 104 the cutter will be moved downwardly and caused to sever such stamps as may have been projected beyond the guideways and these stamps will drop through the delivery chute 16 to the delivery pocket 17.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a stamp vending machine, a feeding device to advance a stamp strip, a detent to enter perforations between adjacent stamps and hold said strip against movement, means to move said detent to an inoperative position, an intermediate member operatively connected with said means and having a plurality of contact parts, an actuating member movable into operative relation to any one of said contact parts, coin controlled means to control the position of said actuating member, and means to impart operative movement to said actuating member.

2. In a stamp vending machine, a feeding device to advance a stamp strip, a detent to enter perforations between adjacent stamps and hold said strip against movement, means

to move said detent to an inoperative position, an intermediate member operatively connected with said means and having a plurality of contact parts, an actuating member movable into operative relation to any one of said contact parts, coin controlled means to control the position of said actuating member, means to impart operative movement to said actuating member and move said intermediate member to a position determined by the contact part which is engaged by said actuating member, and means to retain said intermediate part in the position to which it is moved when one of said contact parts is engaged by said actuating member a longer time than it will be retained in the position to which it is moved when another of said contact parts is engaged by said actuating member.

3. In a stamp vending machine, a feeding device to advance a stamp strip, a detent to enter perforations between adjacent stamps and hold said strip against movement, means to move said detent to an inoperative position, an intermediate member operatively connected with said means and having a plurality of contact parts, an actuating member movable into operative relation to any one of said contact parts, coin controlled means to control the position of said actuating member, said contact parts being so arranged that said intermediate member will be moved a greater distance when one of said contact parts is engaged by said actuating member than it will be moved when another of said contact parts is moved by said contact member, a detent to retain said intermediate member in the position to which it is moved when the first mentioned contact part is engaged by said actuating member, and means for imparting operative movement to said actuating member.

4. In a stamp vending machine, feeding rollers to advance a stamp strip, a detent to normally hold said strip against movement, means to move said detent to an inoperative position, a pivoted member operatively connected with said means and having a plurality of contact parts, an actuating device comprising an arm and a finger pivotally mounted on said arm for movement into operative relation to a selected contact part of said pivoted member, coin controlled means for controlling the position of said actuating finger, and means for imparting operative movement to said actuating device.

5. In a stamp vending machine, feeding rollers to advance a stamp strip, a detent to normally hold said strip against movement, means to move said detent to an inoperative position, a pivoted member operatively connected with said means and having a plurality of contact parts, an actuating device comprising an arm and finger pivot-

ally mounted on said arm for movement into operative relation to a selected contact part of said pivoted member, coin controlled means for controlling the position of said 5 actuating finger, means for imparting operative movement to said actuating device, and means controlled by said pivoted member to hold one of said feed rollers out of contact with said stamp strip when said 10 pivoted member is in its normal position.

6. In a stamp vending machine, a feeding device to advance a stamp strip comprising a driven roller and a pressure roller, a movable support for said pressure roller, a 15 spring acting on said support to move said pressure roller toward said driven roller, a detent to normally hold said stamp strip against movement, means to move said detent to an inoperative position, a pivoted 20 member operatively connected with said means and having a plurality of contact parts, an actuating device having a finger movable into operative relation to a selected contact part of said pivoted member, coin 25 controlled means to control the position of said finger, means to impart operative movement to said actuating device, means to move said pressure roller away from said driven roller, and a detent operatively connected 30 with said pivoted member and arranged to engage said support and retain said pressure roller in its retracted position.

7. In a stamp vending machine, feeding mechanism to advance a stamp strip, a detent to normally hold said stamp strip against movement, means to move said detent to an inoperative position, an intermediate member operatively connected with said means and having a plurality of 35 contact parts, an actuating device having a finger movable into operative relation to a selected contact part of said intermediate member, means to impart movement to said actuating device, a coin chute having means 40 to support a coin therein, a movable arm having a part arranged to enter said coin chute and to engage the edge of a coin therein, whereby the amount of movement imparted to said arm will be determined by 45 the size of said coin, and a second arm connected with the first mentioned arm for movement thereby and having means to control the position of said actuating finger.

8. In a stamp vending machine, feeding 55 mechanism to advance a stamp strip, a detent to normally hold said stamp strip against movement, means to move said detent to an inoperative position, an intermediate member operatively connected with 60 said means and having a plurality of contact parts, an actuating device having a finger movable into operative relation to a selected contact part of said intermediate member, means to impart movement to said 65 actuating device, a coin chute having means

to support a coin therein, a movable arm having a part arranged to enter said coin chute and to engage the edge of a coin therein, whereby the amount of movement imparted to said arm will be determined by 70 the size of said coin, and a second arm connected with the first mentioned arm for movement thereby and having a part to engage said actuating finger and control the movement thereof, and yieldable means to hold said actuating finger normally in engagement with said part of said second arm. 75

9. In a stamp vending machine, feeding mechanism to advance a stamp strip, a detent to normally hold said stamp strip 80 against movement, means to move said detent to an inoperative position, an intermediate member operatively connected with said means and having a plurality of contact parts, an actuating device having a 85 finger movable into operative relation to a selected contact part of said intermediate member, means to impart movement to said actuating device, a coin chute having means to support a coin therein, a movable arm 90 having a part arranged to enter said coin chute and to engage the edge of a coin therein, whereby the amount of movement imparted to said arm will be determined by the size of said coin, a second arm connected 95 with the first mentioned arm for movement thereby and having a part to engage said actuating finger and control the movement thereof, yieldable means to hold said actuating finger normally in engagement with 100 said part of said second arm, yieldable means for moving said part of the first mentioned arm into said chute, and means for withdrawing said arm from said chute.

10. In a stamp vending machine, feeding mechanism to advance a stamp strip, a detent to normally hold said stamp strip against movement, means to move said detent to an inoperative position, an intermediate member operatively connected with said 105 means and having a plurality of contact parts, an actuating device having a finger movable into operative relation to a selected contact part of said intermediate member, means to impart movement to said actuating device, a coin chute, a stop movable into and out of a position to support a coin in said chute, a movable arm having a part arranged to enter said coin chute and engage the edge of a coin which is supported by said stop, a second arm connected with the first mentioned arm for movement thereby and having means to control the position of said actuating finger, said part of said 110 first mentioned arm having a portion arranged to extend above the coin with which it is in engagement and support a second coin, and means for withdrawing said stop to release the first mentioned coin and for retaining said part of said arm in a position 115 120 125 130

to support said second coin until said stop had been returned to its operative position.

11. In a stamp vending machine, feeding mechanism to advance a stamp strip, a detent to normally hold said stamp strip against movement, means to move said detent to an inoperative position, an intermediate member operatively connected with said means and having a plurality of contact parts, an actuating device having a finger movable into operative relation to a selected contact part of said intermediate member, means to impart movement to said actuating device, a coin chute having means to support a coin therein, a movable arm having a part arranged to enter said coin chute and to engage the edge of a coin which is supported by said stop, a second arm connected with the first mentioned arm for movement thereby and having means to control the position of said actuating finger, a movable member arranged to be engaged by that side of said coin opposite the side engaged by the first mentioned arm and having a part movable into and out of a position to support said coin after it has been released by said stop, a spring acting on said movable member to move said part into coin supporting position, yieldable means to press said part of said first mentioned arm against said coin, and means to limit the movement of said movable member by said coin.

12. In a stamp vending machine, feeding mechanism to advance a stamp strip, a detent to normally hold said stamp strip against movement, means to move said detent to an inoperative position, an intermediate member operatively connected with said means and having a plurality of contact parts, an actuating device having a finger movable into operative relation to a selected contact part of said intermediate member, means to impart movement to said actuating device, a coin chute having means to support a coin therein, a movable arm having a part arranged to enter said coin chute and to engage the edge of a coin therein, whereby the amount of movement imparted to said arm will be determined by the size of said coin, a second arm connected with the first mentioned arm for movement thereby and having means to control the position of said actuating finger, a detent arranged to engage said intermediate member when the latter has been moved to a predetermined position, a cam actuated means for imparting operative movement to said actuating device, for moving the last mentioned detent to an inoperative position and for withdrawing said first mentioned arm from said coin chute.

13. In a stamp vending machine, feeding mechanism to advance a stamp strip, a detent to normally hold said stamp strip against movement, means to move said

detent to an inoperative position, an intermediate member operatively connected with said means and having a plurality of contact parts, an actuating device having a finger movable into operative relation to a selected contact part of said intermediate member, means to impart movement to said actuating device, a coin chute having means to support a coin therein, a movable arm having a part arranged to enter said coin chute and to engage the edge of a coin therein, whereby the amount of movement imparted to said arm will be determined by the size of said coin, and a second arm connected with the first mentioned arm for movement thereby and having means to control the position of said actuating finger, a detent arranged to engage said intermediate member when the latter has been moved to a predetermined position, and operating mechanism having means for imparting operative movement to said actuating device, for moving the last mentioned detent to an inoperative position and for withdrawing said first mentioned arm from said chute.

14. In a stamp vending machine, feeding mechanism to advance a stamp strip, a detent to normally hold said stamp strip against movement, means to move said detent to an inoperative position, an intermediate member operatively connected with said means and having a plurality of contact parts, an actuating device having a finger movable into operative relation to a selected contact part of said intermediate member, means to impart movement to said actuating device, a coin chute having means to support a coin therein, a movable arm having a part arranged to enter said coin chute and to engage the edge of a coin therein, whereby the amount of movement imparted to said arm will be determined by the size of said coin, a second arm connected with the first mentioned arm for movement thereby and having means to control the position of said actuating finger, a detent arranged to engage said intermediate member when the latter has been moved to a predetermined position, a cam actuated means for imparting operative movement to said actuating device, for moving the last mentioned detent to an inoperative position and for withdrawing said first mentioned arm from said coin chute.

15. In a vending machine comprising an actuating device having a part movable into different positions to determine the number of articles delivered, a selecting mechanism comprising a coin chute, a stop movable into and out of a position to support a coin within said chute, a cam to actuate said stop, an arm having a part arranged to enter said coin chute and engage a coin therein, said part of said arm having a portion to

extend above said coin and support a second coin in said chute, means connected with said arm to control the position of said part of said actuating device, and a cam to control the position of said arm, said cams being so arranged with relation one to the other that when said stop has been moved to an inoperative position said portion of said arm will be in a position to interrupt the movement of a coin through said chute and support said coin until said stop has been returned to its operative position.

16. In a vending machine comprising an actuating device having a part movable into different positions to determine the number of articles delivered, a selecting mechanism comprising a coin chute, a stop movable into and out of a position to support a coin within said chute, means to actuate said stop, an arm having a part arranged to enter said chute and engage the edge of a coin supported therein by said stop, means connected with said arm for controlling the position of said part of said actuating device, means for imparting movement to said actuating device and for withdrawing said arm from said coin chute, and means for interrupting the movement of said coin after it has been released by said stop and supporting the same in a position in which it will be exposed to view.

17. In a vending machine, comprising an actuating device having a part movable into different positions to determine the number of articles delivered, a selecting mechanism comprising a coin chute, a stop movable into and out of a position to support a coin within said chute, means to actuate said stop, an arm having a part arranged to enter said chute and engage the edge of a coin supported therein by said stop, means connected with said arm for controlling the position of said part of said actuating device, means for imparting movement to said actuating device and for withdrawing said arm from said coin chute, an arm pivotally mounted adjacent to said coin chute and having a part arranged to be engaged by that side of said coin opposite the first mentioned arm, a spring to resist the movement of the last mentioned arm by said coin, means to limit the movement of said last mentioned arm by said coin, and a part carried by said last mentioned arm and arranged to be moved into the path of said coin when the latter moves out of engagement with said part of said last mentioned arm.

18. In a stamp vending machine, feeding mechanism to advance a stamp strip, a detent to normally hold said stamp strip against movement, means to move said detent to an inoperative position, an intermediate member operatively connected with said means and having a plurality of con-

tact parts, an actuating device having a finger movable into operative relation with a selected contact part of said intermediate member, an operating shaft, a cam carried by said operating shaft to impart operative movement to said actuating device, a detent arranged to engage said intermediate member when the latter has been moved to a predetermined position by said actuating device, a part carried by said operating shaft to move the last mentioned detent to an inoperative position, a coin chute, a stop movable into and out of a position to support a coin in said chute, a cam carried by said operating shaft to control the position of said stop, an arm pivotally mounted adjacent to said coin chute and having a part adapted to enter said chute and engage the edge of a coin supported therein by said stop, a spring acting on said arm to move said part thereof into said chute, a second arm rigidly connected with the first mentioned arm and having a part to engage said actuating finger and control the position thereof, an arm arranged to act on the first mentioned arm to withdraw the same from said coin chute, and a cam on said operating shaft to actuate the last mentioned arm.

In testimony whereof, I affix my signature hereto.

ABRAM LOCKHEART ZENT.
